UNITED STATES PATENT OFFICE.

JOHN F. STANDISH, OF WINTHROP, MASSACHUSETTS, ASSIGNOR TO UNITED SHOE MACHINERY COMPANY, OF PATERSON, NEW JERSEY, A CORPORATION OF NEW JERSEY.

NAIL-ASSORTING MACHINE.

1,247,344.

Specification of Letters Patent. Patented Nov. 20, 1917.

Application filed January 12, 1914. Serial No. 811,688.

To all whom it may concern:

Be it known that I, JOHN F. STANDISH, a citizen of the United States, residing at Winthrop, in the county of Suffolk and State of Massachusetts, have invented certain Improvements in Nail-Assorting Machines, of which the following description, in connection with the accompanying drawings, is a specification, like reference characters on the drawings indicating like parts in the several figures.

This invention relates to machines for assorting nails, and is intended primarily as an improvement in nail assorting machines having nail guiding raceways of the type disclosed in United States Letters Patent to Mayo *et al.* 707,138, August 19, 1902.

The present invention, like that disclosed in the said patent, is herein described and illustrated as embodied in a nail assorting machine in which nails are received upon, and guided by, a raceway disposed in a vertical plane and having a groove or guideway in its upper edge for guiding the nails toward their destination. Certain features of the present invention, however, are not limited in their usefulness to this particular type of raceway but may be embodied in a variety of other specific forms.

In machines of the type disclosed in the patent above referred to the practice has been, when the number of nails required in a group was less than the number of raceway grooves, to stop the feed of nails from the extra grooves by inserting stop pins or nails in holes in such grooves. This has sometimes caused the unused nails to accumulate and clog the machine so that it would not properly deliver nails from the raceways which it was desired to use.

The object of the present invention is to provide a nail assorting machine, having one or more nail guiding raceways, with simple and effective means for preventing the delivery of nails by a raceway or raceways and for avoiding clogging of the machine with unused nails.

With this object in view, a feature of the invention consists in a raceway comprising a plurality of sections, one of which is arranged to be moved out of alignment with the rest, to interrupt the continuity of the raceway so that nails shall no longer be delivered from it. Preferably the raceway is disposed in a vertical plane and the movable

section is pivoted so that it may be moved out of said plane, leaving a space into which nails traveling along the raceway will drop, to be returned to the source of supply. Thus all danger of clogging or piling up of nails is avoided and the delivery or non-delivery of nails by the raceway is easily controlled.

A further feature of the invention resides in the combination of a plurality of raceways, some of which are continuous and some of which are of the sectional construction above described. When nails are to be supplied in groups of various numbers, the number of continuous raceways will preferably correspond to the minimum number of nails in any group and the remainder of the raceways will be sectional. Provision will thus be made for cutting off the supply of nails from as many raceways as necessary, leaving only the desired number of nails to be delivered.

In addition to the features above mentioned, the machine herein disclosed also embodies certain features of construction and arrangements of parts, the advantages of which will be obvious to those skilled in the art from the following description.

In the drawings,

Figure 1 is a perspective view of a portion of a nail assorting machine embodying the invention;

Fig. 2 is a similar view upon an enlarged scale of a series of raceway sections detached from the machine;

Fig. 3 is a side view, partly in section, of a raceway section and its mounting; and

Fig. 4 is a fragmentary view showing two raceway sections in end elevation.

Referring to the drawings, 2 indicates generally a series of raceways corresponding to the upper raceway section of the machine of the patent heretofore mentioned. As shown herein, a plurality of continuous, parallel raceways 4, having nail guiding grooves 6 in their upper edges, are rigid with, and preferably are a part of, the casting 8 which forms the bed piece and support for the series. The number of these continuous raceways is shown as five, since that is the minimum number of nails which it is desired to deliver to the heel attaching machine with which this particular machine is to be used, but this number may be more or less, according to the use to

which the nail distributing machine is to be put, and still be within the scope of the invention.

Each of the other raceways of the series has portions 10 and 12, which are also a part of the casting 8, and an intermediate movable section 14. The sections 14 have pivots 16 and 18 projecting from their ends in a line parallel to the groove 6. The pivots 16 and 18 have their bearings in angular supports 20 and 22, respectively, which, in turn, are secured by bolts or otherwise to the casting 2 in such a manner that when the sections 14 are vertical their grooves will be in alinement with corresponding grooves in the portions 10 and 12. When all the sections 14 are in this position all the raceways will be, in effect, continuous and nails will be supplied by all of them. When, however, the number of nails required is less than the number of raceway grooves, the feed of nails from the extra grooves may be stopped by turning a suitable number of sections 14 upon their pivots out of the plane of their contiguous portions 10 and 12, into the inclined position shown at 24 in Fig. 1, and by dotted lines in Fig. 4, whereupon the nails coming along the portions 12 of the grooves of those raceways will fall into the spaces 26 between the raceways and be returned to the source of supply.

The lower ends of the upper stationary portions 12 of the raceways are shaped to fit over the top and rear side of the angular support 22 so that the end of each of these sections is flush with the adjacent end of its corresponding movable section 14. The upper ends of the lower stationary sections 10 are similarly shaped to fit the lower angular support 20.

For each raceway section 14 there are stop pins 28 and 30 which limit the movement of the section 14 into vertical and inclined position, respectively. A pin 32, sliding in a hole in the rear end of the section and pressed outward by a spring 34, enters depressions 36 and 38 in the support 22 to secure the section in either of the positions described.

Preferably the continuous raceways are located in the center of the machine, with the sectional raceways upon either side of, and in parallel relation to, them, because in the operation of this type of machine there is greater certainty of a demand for a full supply of nails upon the center raceways than upon those at the extreme sides.

Having described the invention, what is claimed as new and desired to be secured by Letters Patent is:—

1. In a nail assorting machine, a nail raceway comprising separated sections having in their upper faces alined grooves formed to support and guide nails lying

prone, and an intermediate section having in its upper edge a similar groove, said intermediate section being movable from a position in which its groove is in alinement with the first-mentioned grooves to a position in which its groove is out of alinement with said first-mentioned grooves. 70

2. In a nail assorting machine, a nail raceway comprising separated sections having in their upper faces alined nail guiding grooves and an intermediate section in the form of a flat plate having in its upper edge a similar groove so disposed that when said flat plate is in a vertical plane the groove in its upper edge forms a continuation of the grooves in the separated sections, said flat plate being movable out of said vertical plane into a position where the continuity of the grooves is interrupted. 75 80

3. In a nail assorting machine, a nail raceway comprising separated sections having in their upper faces alined nail guiding grooves, and an intermediate section in the form of an elongated, flat plate having in its upper edge a similar groove, said plate being 85 mounted for pivotal movement, about an axis longitudinal thereof, from a position in a vertical plane in which all the grooves mentioned are in alinement to a position in an inclined plane wherein the groove in the 90 plate is out of alinement with the grooves in the separated sections. 95

4. In a nail assorting machine, a nail raceway comprising separated sections having in their upper faces alined grooves formed 100 to support nails arranged end to end and to guide said nails for lengthwise movement, and an intermediate section provided with a similar groove movable from a position in which its groove is in alinement with the first-mentioned grooves to a position in which its groove is out of alinement with, and parallel to, said first mentioned grooves. 105

5. In a nail assorting machine, a nail raceway having a section movable into and out 110 of operative relation to the remainder of the raceway, and means for yieldingly securing said movable section against manual displacement from either of said relations. 115

6. In a nail assorting machine, a sectional 115 nail guiding raceway disposed in a vertical plane, one of the sections being mounted for movement out of said vertical plane, and means for securing the movable section either in or out of the vertical plane. 120

7. In a nail assorting machine, a raceway section having a nail guiding groove disposed in the same general direction as the raceway section and being mounted for pivotal movement about an axis parallel to the 125 groove. 130

8. In a nail assorting machine, a plurality of raceways, some of said raceways being continuous at all times and others of said raceways having movable nail carrying sec-

- tions, so arranged that their continuity may be interrupted.
9. In a nail assorting machine, a permanently continuous nail guiding raceway and a plurality of similar raceways upon opposite sides of, and parallel to said continuous raceway, but each having a movable nail carrying section by movement of which its continuity may be interrupted.
- 10 10. In a nail assorting machine, a plurality of parallel raceways separated by spaces, one of the raceways being provided with a nail carrying section movable out of alinement with the remainder of the raceway to interrupt its continuity and permit nails traveling upon it to drop into one of the spaces.

11. Nail assorting mechanism including a raceway having stationary alined end sections, and an intermediate section disposed between said end sections and movable into or out of line therewith.

12. Nail assorting mechanism including a raceway having stationary end sections, supports disposed beneath the adjacent ends of the stationary sections, and an intermediate section pivotally mounted in said supports.

In testimony whereof I have signed my name to this specification in the presence of two subscribing witnesses.
